[57] CLAIM

The ornamental design for a dispensing spigot for an insulated beverage container, substantially as shown and described.

DESCRIPTION

FIG. 1 is a left side elevational view of a dispensing spigot for an insulated beverage container showing our new design, the right side being a mirror image thereof.

FIG. 2 is a front elevational view thereof;

FIG. 3 is a top plan view thereof;

FIG. 4 is a bottom plan view thereof; and

FIG. 5 is a rear elevational view of the spigot.

*Fig. 1**Fig. 2**Fig. 3**Fig. 4**Fig. 5*
